CLAMSHELL BUCKET

Jean Georges Caillard, Le Havre, France

Application December 15, 1947, Serial No. 791,725
In France March 24, 1947

1 Claim. (Cl. 37—184)

1

My invention relates to improvements in clamshell buckets.

Clamshell buckets, as used to carry loose goods, usually comprise two shells pivoted on a cross-part or strap and connected to the bucket head which is fixed to the cable carrying the whole device.

The closing of the bucket on the materials to be carried is obtained by bringing together the above-mentioned cross-part and bucket head.

It was found that the force necessary to bring together the shells is low at the beginning of the closing movement and then increases progressively until it becomes large at the end of such closing movement. It follows that, particularly with certain materials which are difficult to grab such as ores, coal in large cobbles, etc., the blade-edges of the shells have a tendency to be forced upwards, so that part of the materials lying between the said edges is left on the spot.

The object of this invention is to provide a clamshell bucket which overcomes such difficulties.

According to this invention, there is added to one of the parts to be brought together (that is the cross-part and the bucket head) a rocking lever, one of the arms of which is connected by a tie-bar to the other part, while the second arm of said lever is fixed to the draw-rope or cable controlling the closing movement of the bucket. The lever is so arranged that the arm fixed to the draw-rope is at a small angle, to this rope or cable, at the beginning of the closing movement and at a considerable angle at the end of such movement, while the arm fixed to the draw-bar is at a considerable angle to the said draw-bar at the beginning of the closing movement and is at a small angle to it at the end of said movement.

Due to such an arrangement, the linkage which brings the shells together has a low transmission ratio at the beginning of the closing movement while it has a high transmission ratio towards the end of said closing movement. It follows that the closing movement, while rapid at the beginning, ends slowly and applies a powerful force on the materials to be loaded.

In the annexed drawings:

Figs. 1, 2 and 3 are diagrammatic elevational views of a bucket comprising two shells hinged on a common axis and embodying the features of the present invention.

In Fig. 1 the bucket is shown in the open position.

Fig. 2 shows the bucket in an intermediate po-

sition during the movement which brings the two shells together.

Fig. 3 shows the bucket in the closed position.

Figs. 4 and 5 are diagrammatic elevational views of a bucket comprising shells pivoted around parallel axes and embodying the features of the present invention, Fig. 4 showing the bucket in the open position and Fig. 5 showing it in the closed position.

10 Figs. 6 and 7 are elevational views of a clamshell bucket of the same type as shown in Figs. 1 and 2, but in which the rocking lever is located on the axis of suspension of the head.

Fig. 6 shows the bucket in the open position.

15 Fig. 7 shows the same bucket in its closed position.

The bucket shown in Figs. 1-3 comprises two shells 1 and 1' hinged on a central axis 2.

The said shells are provided with ears 12, 12' 20 on which bars or links 4 and 4' are hinged. These links are also hinged on an axis 5 mounted in the bucket head, which is suspended from a rope 13.

According to Figs. 1-3 a lever 6 is arranged on 25 axis 2. The said lever is hinged at 7 on one end of a draw-bar 8, the other end of which is hinged on axis 5 of the head.

30 Axis 5 is provided with an idle pulley 14 around which draw-rope or cable 10 which controls the bringing of the two shells together is led. This rope or cable is attached to that end 9 of lever 6 which is remote from hinge 7.

The device operates in the following manner:

When the bucket is open, as shown in Fig. 1, 35 and it is desired to close it, a pull is applied to rope or cable 10. Lever 6 is thus caused to revolve about hinge 7 while bearing on draw-bar 8, and axis 2 is lifted upwardly and both shells are thus rotated around the said axis.

40 At the beginning of the movement the direction of arm 2, 9 of lever 6 is not remote from the direction of the pull applied by rope 10, while arm 2, 7 is at a considerable angle to draw-bar 8. It follows that, for a small travel of rope or cable 10, axes 2 and 5 are appreciably brought together. The closing movement of the bucket is thus relatively swift during this first stage.

45 It may be seen by comparison of Figs. 1 and 2, that as the pull of rope 10 is continued, the angle between arm 2—9 and rope 10 increases, and conversely the angle between arm 2—7 and draw-bar 8 decreases.

During the final stage of the closing movement (from the position shown in Fig. 2 to that shown 55 in Fig. 3) arm 2—9 of lever 6 is at considerable

angle to the line of traction of cable 10, which thus acts with a large leverage. During the same stage, arm 2-7 is at a small angle to draw-bar 8. The closing movement is thus slackened, but the force tending to bring the shells together is greatly increased. A perfect filling of the bucket is thus obtained.

Figs. 4 and 5 show my invention as applied to a bucket comprising two shells 1 and 1', hinged on a cross-part or strap 20, along two parallel axes 21 and 21' respectively and provided with toothed sectors 22 and 22', which mesh with one another. Shell 1 is hinged at 23 on a bar 24 the other end of which is in turn hinged on a lever 25 hinged at 23' on shell 1'. The said lever, the axis of suspension of which is shown at 26, is hung on rope 27 which supports the whole bucket.

According to my invention, a lever 6 is pivoted at 2 on strap 20. One arm of this lever is hinged at 1 on a draw-bar 8 at the other end of which is hinged on lever 25 in the vicinity of axis of suspension 26. The other arm of lever 6 is attached at 9 to draw-rope 10, which is led over an idle pulley 28. Both arms of lever 6 have the same direction with reference to draw-bar 8 and draw-rope 10 as already shown in Figs. 1-3 and the device gives the same advantages as that previously shown.

In the form of device according to Figs. 6 and 7, the rocking lever is located on the bucket head. One of its arms is connected, through a draw-rod, to the cross-part of the bucket, while its other arm is attached to the closing rope which is led around an idle pulley pivoted on the said cross-part.

These figures shown again at 1 and 1' both shells, hinged on axis 2 and provided with ears 12 and 12' which are connected by means of bars 4 and 4' to axis 5 on the bucket head hanging from rope 13.

In axis 5 of the head there is provided a lever 6, one end of which is connected to one end of a draw-rod 8, the other end of draw-rod 8 being hinged to axis 2 about which the shells are arranged to turn.

Draw-rope 10 is led over an idle pulley 31, pivoted on axis 5 and thence on a counter-pulley 32 which runs idle on axis 2, and finally draw-rope 10 is attached to lever 6 at its end 9 remote from end 1.

At the beginning of the movement, arm 5-9 of lever 6 has nearly the same direction as rope 10, attached at 9 and on the contrary, arm 5-7 is at a considerable angle to draw-bar 8. A small

travel of rope 10 thus causes an appreciable drawing together of axes 2 and 5, so that the closing movement is relatively swift during its initial stage.

As the said movement is carried on, the angle between arm 5-9 and rope 10 increases, while the angle between arm 5-7 and draw-rod 8 decreases.

As the movement approaches its end, arm 5-9 is at a considerable angle to rope 10 fixed at 9, while the angle between arm 5-7 and tie-rod 8 is reduced. The closing of the shells thus ends slowly, but with a large force, which ensures a perfect filling of the bucket.

The arrangement and operation of the above described rocking lever are independent of the particular type of bucket used and the invention may consequently be used with buckets of quite dissimilar types.

Moreover it appears that my invention is not to be limited to the several devices illustrated by way of examples and that many modifications may be used within the scope of my invention as set forth in the appended claim.

I claim:

A clamshell bucket comprising two shells, axis means pivotally connecting said shells, a head, links pivotally connected at one end to said shells at a region spaced from the axis means, means connecting the other ends of said links to said head, a rocking bell crank lever pivotally mounted on said axis means intermediate its ends, a draw bar connected at one end to the head and at its other end with one end of the bell crank lever, and a draw rope carried by said head and connected to the other end of the bell crank lever, operable to close the shells of the bucket, the arm of the bell crank lever to which the draw bar is connected lying at small angle with said draw bar when the shells are nearly closed, and the arm of the bell crank lever connected to the draw rope lying at an angle close to 90° with the draw rope when the shells are nearly closed.

JEAN GEORGES CAILLARD.
